UNITED STATES PATENT OFFICE.

RICHARD WILDE, OF TORONTO, ONTARIO, CANADA.

DEVICE FOR EFFECTING COMPLETE COMBUSTION IN FURNACES.

No. 830,870.

Specification of Letters Patent.

Patented Sept. 11, 1906.

Application filed September 1, 1904. Serial No. 223,055.

To all whom it may concern:

Be it known that I, RICHARD WILDE, engineer, residing at the city of Toronto, in the county of York, in the Province of Ontario, Canada have invented certain new and useful Improvements in a Device for Effecting Complete Combustion in Furnaces, being an improvement on my Canadian Patent No. 85,930, issued the 15th day of March, 1904; and I do hereby declare that the following is a full, clear, and exact description of the same.

The objects of my invention are to construct an apparatus to be arranged in combination with the boiler-setting, whereby I effect a complete combustion of the products that pass from the furnace by returning them to the furnace the second time. The apparatus is so arranged that I do not introduce foreign elements into the furnace, thereby preventing the possibility of checking the combustion.

The device is so arranged that it collects from the stack and returns and distributes to several points in the furnace the unconsumed carbonous gases and at the same time at a temperature equal to that in the combustion-chamber, so that they are in a state that they will readily be consumed.

I attain these objects by the apparatus as illustrated in the accompanying drawings, in which—

Figure 1 is a longitudinal sectional view, and Fig. 2 is a cross-sectional view, on lines 35 *a a*, Fig. 1. Fig. 3 is a perspective detail of the perforated pipe and tubular connection.

Like letters refer to like parts throughout the specification and drawings.

I show in the drawings, in combination 40 with my invention, an ordinary boiler and boiler-setting, consisting of the boiler *a*, combustion-chamber *b*, bridge-wall *c*, ash-pit *d*, grate-bars *e*, furnace *f*, dead-plate *g*, fire-door *h*, back arch *i*, and stack *j*. Arranged in the back end of the combustion-chamber *c* is a reservoir or chamber *k*, arranged to extend across the entire width of the combustion-chamber and may be built in of fire-bricks or consist of a metal boxing 45 and into which the unconsumed products of combustion are conveyed and from which they are distributed to the furnace.

Set on the back arch *i* of the boiler-setting 50 is a rotary fan *l*. The fan may be of any convenient type, consisting of the usual fan-casing and fan and provided with the usual

drive shaft and pulley projecting at right angles through the side. Extending parallel with the boiler *a* and communicating with the stack *j* and side face of the fan-casing is 60 a tubular connection *m*, by which the unconsumed products may be drawn into the fan.

Extending outwardly from the perimeter of the fan-casing, one from the top and one from the bottom, are two tubular branches *n* 65 and *n'*, which are bent at right angles and adapted to extend down the sides of the boiler-setting and enter into each end of the reservoir or chamber *k* and convey to the reservoir the unconsumed products that are 70 drawn by the fan from the stack through the tubular connection *m*.

Extending from the front of the reservoir and through the upper part of the center of the bridge-wall is a discharge-pipe *o*. The 75 pipe *o* is set in the floor of the combustion-chamber *c* and may be incased in fire-clay or set in fire-bricks to prevent it from burning out, and extending from the front of the reservoir and passing into the ash-pit near the 80 bottom are two discharge-pipes *p*. The two discharge-pipes *p* are parallel with one another and are adapted to discharge one on each side of the ash-pit.

Set across the ash-pit beneath the grate-bars and adjacent to the dead-plate *g* is a perforated pipe *q*, and coupled with each end of the perforated pipe *q* and extending downward and backward to the reservoir *k* are two feed-pipes *r*. The pipes *o*, *p*, *q*, and *r* communicate with the reservoir and furnace *f* and are for the purpose of equally distributing the products of combustion drawn from the stack by the fan and forced by the fan into the reservoir and from the reservoir 95 into the furnace.

Arranged in any convenient position in the tubular connection *m* is an oxygen-damper *s*, through which air may be drawn into the fan and supplied to the reservoir along with 100 the unconsumed products of combustion, and arranged in each of the downward-extending sections of the tubular branches *n* and *n'* are dampers *t* and *t'*, by which the amount of pressure may be regulated in the 105 reservoir and from the reservoir to the fire.

Passing around the pulley *u* is a drive-belt *v*, which may be carried to any convenient means for deriving motion.

The operation is as follows: As the unconsumed products of combustion are passing off through the stack they are sucked into

the tubular connection *m* by the suction created by the fan. They then pass through the fan-casing and are forced from the fan down through the branches *n* and *n'* into the reservoir or chamber *k*, and from the reservoir *k* they are distributed to the furnace through the discharge-pipes *o*, *p*, and *r*, respectively

5 The fan is to be driven by any suitable motive power and may be set to any desired speed. The fan also draws in with the unconsumed products of combustion oxygen through the damper *s* in the connection *m* and forces all down into the reservoir.

10 It will be understood from the nature of the device the fan acts as a factor in supplying the reservoir and also acts as a means of pressure by which the products may be forced from the reservoir into the furnace.

15 What I claim as new, and desire to secure by Letters Patent, is—

20 1. In combination with a furnace a device for the purpose specified, a reservoir-chamber, said reservoir-chamber suitably arranged in the combustion-chamber, discharge-pipes leading from the said reservoir-chamber, said pipes communicating with a perforated pipe, said perforated pipe arranged in the furnace; in close proximity with the grate-bars, discharge-pipes also 25 leading from the said reservoir-chamber into the furnace, a rotary fan arranged to draw the unconsumed products from the stack

30 through a tubular connection, said tubular connection arranged between the stack and the side face of the said fan, tubular conveying branches arranged between the fan and the said reservoir, suitable means for rotating the said fan, substantially as specified. 35

2. In combination with a furnace a device for the purpose specified, consisting of a reservoir-chamber, said reservoir-chamber suitably arranged in the combustion-chamber, a rotary fan, said fan arranged on the back arch of the said combustion-chamber, a tubular connection arranged between the stack 40 and the side face of said fan, an air-inlet damper arranged in the said tubular connection, tubular conveying branches arranged between the said fan and reservoir-chamber, regulating-dampers arranged in the said connection, discharge-pipes leading from the reservoir into the furnace, a perforated pipe arranged in the said furnace, in close proximity to the grate-bars, feed-pipes communicating between the said reservoir-chamber and the said perforated pipe, suitable means for operating the said rotary fan, 45 substantially as specified. 50

Signed at Hamilton this 10th day of August, 1904.

RICHARD WILDE.
